[57] **CLAIM**

The ornamental design for a handset telephone, as shown and described.

DESCRIPTION

FIG. 1 is a partial left side, and partial front perspective view of a handset telephone showing my new design; FIG. 2 is a front elevational view thereof shown in open position;

FIG. 3 is a left side elevational view, the side opposite being a mirror image;

FIG. 4 is a top plan view thereof;

FIG. 5 is a bottom plan view thereof;

FIG. 6 is a rear elevation view thereof, shown in opened position; and

FIG. 7 is a front elevational view thereof, shown in closed position.

FIG. 1

FIG. 2

FIG. 3

FIG. 4

FIG. 5

FIG. 6

FIG. 7
